UNITED STATES PATENT OFFICE.

JOHN ROBERTS BOLTON, OF BROOKLYN, NEW YORK, ASSIGNOR TO A. G. SPALDING & BROS., OF NEW YORK, N. Y., A CORPORATION OF NEW JERSEY.

GOLF-PRACTICE NET.

Application filed September 17, 1921. Serial No. 501,264.

To all whom it may concern:

Be it known that I, JOHN ROBERTS BOLTON, a subject of Great Britain, residing in the borough of Brooklyn, of the city of New York, in the State of New York, have invented certain new and useful Improvements in Golf Practice Nets, of which the following is a specification, reference being had to the accompanying drawing, forming a part hereof.

In Letters Patent of the United States No. 920,907 dated May 11, 1909, there is shown and described a golf practice net which has proved to be very useful for practice outdoors and indoors. The construction, as there disclosed, however, has been found to be susceptible of improvements which constitute the subject matter of the present application. These improvements reside primarily in the provision of side extension nets to form an alley of some length thereby confining the flight of the ball more effectively than heretofore, and in detachable rigging associated with the net supports for giving a greater degree of rigidity while permitting greatest facility of assembling and disassembling. In the device covered by said patent there is no provision for adjusting of any of the stays or struts nor is there any interconnection thereof whereby all may be tied into a more or less rigid structure. In accordance with the present invention the crossed side members are interconnected by means of adjustable stays which may be anchored to transverse struts extending between corresponding members. The transverse struts are further adapted to be engaged positively with the crossed members by conjugal elements easy of manipulation for assembling and disassembling. Additional hooks may be employed for engagement with certain of the elements for interconnection and greater rigidity.

Another feature of the invention has to do with the means for supporting the extension sides of the net in such manner as to space them from the supports and avoid the chance of impact of the ball and rebounding.

All of the advantages herein indicated will be described with greater particularity in connection with the accompanying drawing, wherein—

Figure 1 is a view in perspective of the improved practice net showing the exten-

sion sides and the improved connections which lend rigidity.

Figure 2 is a detail view of a joint between a strut and a side member taken on the plane indicated by the line 2—2 of Figure 1 and looking in the direction of the arrows.

Figure 3 is a detail sectional view through the side member of Figure 2 and showing the key-hole slot and joint between a strut and a side member.

Figure 4 is a detail view showing how a cross strut is tied to a stay and hook which engage other members.

Figure 5 is a detail view showing an extension hook for the net support to hold it spaced from a standard.

In general appearance and uses the improved net resembles that shown in the above mentioned patent. The supporting frame for the net comprises a double set of crossed members *a*, *a'* and *b*, *b'*, pivoted, respectively, at *c*, *d*. The corresponding members *a*, *b* are connected adjacent their upper ends by a transverse strut *e* which, in accordance with the present invention, may be readily engaged or disengaged with the respective members as when the frame is to be set up or collapsed. One convenient form of joint is illustrated in detail in Figures 2 and 3. As there shown the member *a* is provided with a plate *a²* in which is a key-hole slot *a³*. The strut *e* is slotted adjacent its end, as at *e'*, and is adapted to enter the enlarged portion of the key-hole slot *a³* and be slid downward until the slot *e'* and, perhaps, the corresponding slot on the opposite side of the strut is firmly engaged with the plate *a²* in the constricted portion of the key-hole slot *a³*. If necessary, the member *a* may be recessed, as at *a⁴*, in line with the key-hole slot *a³* to receive the end of the strut *e*. The other end of the strut *e* is correspondingly formed and engaged with the corresponding elements on the corresponding member *b*, as will be understood.

The lower ends of the corresponding members *a*, *b* may be interconnected in like manner by means of a transverse strut *f*. The lower ends of the other corresponding members *a'*, *b'* may likewise be interconnected by means of a transverse strut *g* which is engaged in similar manner with the members. To the corresponding members *a*, *b*

adjacent their upper ends and preferably on the outer sides thereof may be pivotally supported extension rods h , h' , the supporting bolt h^2 for the rod h being indicated in Figures 2 and 3. The head h^3 of this bolt may 5 overlie the plate a^2 and assist in maintaining it in proper position on the inner face of the member a . The nut h^4 on the outer end of the bolt will permit the rod h to be set 10 at any desired angle. Between the lower end of the rod h and the outer side of the member a may be interposed a washer i through which the bolt h^2 passes. This 15 washer may have twisted around it the end of a wire stay k in which is a turn-buckle k' for adjustment of the length. The lower end of the stay k may be engaged with an eye l supported on the lower transverse strut g . In similar manner a wire stay m with 20 a turn-buckle m' may extend between the upper end of the member b to the opposite lower side of the strut g where it is engaged with an eye l' . The eyes l , l' also carry hooks n , n' , respectively, which may be engaged 25 with eyes n^2 , n^3 secured to the members a' , b' , respectively. The parts described, when properly adjusted and interengaged in the manner indicated, will give rigidity to the saw-buck frames and all stresses thereon will 30 be distributed equally throughout. To increase this rigidity further, additional hooks o , o' are pivoted to one of the members a' , b' of each of the saw-buck frames, respectively, somewhat near the respective pivots c , 35 d , and are adapted to engage eyelets o^2 , o^3 , respectively, on the other members a , b , respectively. The net p may be hooked on to the heads of screws a^5 , b^2 on the upper ends 40 of the corresponding members a , b , respectively, and also to the ends of the extension rods h , the lower end of the net being carried forwardly and anchored on the bases p' , p^2 , respectively, which may be fixed in place. Each of these bases have eyelets p^3 45 to which may be secured stays q , q' , respectively, extending to the upper ends of corresponding members a , b , where they are anchored. Flexible fastenings q^2 may extend

between each of the corresponding members a , b and the stays q , q' somewhere between the ends of the latter. This rigging insures additional stability and holds the net in proper position at all times.

The construction thus far described incorporates many improvements over that shown in the prior patent referred to but additional features of improvement have to do with extension nets associated with the net p and the means for supporting them. In each of the bases p' , p^2 are carried uprights p^4 . At points beyond the bases p' , p^2 are spaced similar bases, one of which is shown at p^5 , each of such bases also carrying uprights p^6 . In the tops of each of the four standards p^4 , p^6 are supported extension hooks p^7 with which may be engaged the upper edges of the said extension nets r , r' . These nets may also be engaged with the upper ends of the corresponding members a' , b' , respectively. In this way a well defined alley may be set up extending outwardly for some distance from the main net p , so that the flight of the ball is well confined. Of course, if desired either one or both of the extension nets r , r' may readily be removed from the uprights. So long as they are supported on the extension hooks p^7 , it is evident that no ball can be driven against any one of the uprights p^4 , p^6 and all danger of rebounding is eliminated.

I claim as my invention:

The combination with a supporting frame comprising a double set of pivoted crossed members, rods uniting and bracing corresponding crossed members, a net having its upper portion supported by said frame and having its lower end carried forward toward the feet of the player, extension nets extending forwardly from said first named net towards the player to further confine the flight of the ball, and standards having extension hooks to support said extension nets in spaced relation thereto.

This specification signed this 16th day of Sept. 1921.

JOHN ROBERTS BOLTON.
